DRINK MIXER

Max Nathanson, Montreal, Quebec, Canada

Application March 20, 1947, Serial No. 736,008

4 Claims. (Cl. 259—135)

1

This invention relates to improvements in drink mixers for mixing the ingredients used in the preparation of soft drinks.

A particular object of this invention is to provide a mixing device comprising a motor and impeller assembly eccentrically mounted in a supporting structure so that the impeller assembly will be normally biased away from the supporting structure in its inoperative position.

Another object is to provide a switch resiliently biased to open position and arranged to be engaged and closed against the resistance of the switch biasing means by the motor and impeller assembly when the latter is swung in the switch closing direction.

Another object is to provide a switch including a switch actuating element with means for resiliently biasing said element to a switch opening position whereby said element is arranged in the path of movement of a part of the impeller assembly so as to operate it to its inclined position.

A further object of this invention is to provide cup retaining means adapted to hold the mixing cup against displacement while the mixing device is in operation.

A still further object is to provide means for opening and closing the motor circuit when the switch is in its closed circuit position.

Other objects and characteristic features of this invention will be more readily understood from the following detailed description taken in connection with the accompanying drawing in which the single figure is an elevational view of the mixing device embodying my invention.

As shown in the accompanying drawing, 10 designates an upright stand having a pair of laterally extending brackets 11. A motor 12 is supported between brackets 11 to swing about a horizontal axis provided by trunnions 13. A depending impeller assembly 14, comprising an impeller 15 carried by an impeller shaft 16 is secured to motor shaft 17 by a coupling 18. An operating arm 19 has its upper end spot welded or otherwise secured to the side wall of motor 12 to extend downwardly from the side wall of the motor adjacent the upright stand. A cup supporting bracket 20 is secured to stand 10 to support a mixing cup 21.

The stand 10 is hollow and is provided with lead wires 22 having one lead to motor 12 and the other lead to a motor operating switch mechanism 23. The motor and switch mechanism are connected in series to a source of current (not shown) through lead wires 22 by suitable plug 55

2

members 24 connected to the free ends of lead wires 22.

Trunnions 13 extend through openings provided in brackets 11 and are secured in threaded engagement in a motor encircling band 25. The motor 12 is eccentrically supported by said trunnions to assume a tilting position, as shown in dotted line, so that the depending impeller assembly 14 is normally biased away from stand 10 in its inoperative position.

Switch 23 includes an operating element 26 which is biased to open circuit position by resilient biasing means (not shown). This switch operating element is arranged in the path of movement of the eccentrically supported motor and impeller assembly so that it is operated to closed circuit position against the resistance of its biasing means by said assembly when the latter is swung from its tilted to its vertical position. The biasing means of switch 23, acting through switch operating element 26 in the closed circuit condition of the switch, exerts pressure against the motor and impeller assembly to assist in returning said assembly to its normal tilting position.

The operating arm 19 is provided with a cup retaining clip 27 secured thereto by suitable clamping bolts 28. Bolts 28 project through upper and lower slots 29 and 30 provided in the operating arm 19 and are fastened by nuts 31 which are clamped against a clip supporting bar 32 disposed on the opposing face of arm 19 to the clip 27. The upper slot 29 is of greater elongation than slot 30 so as to receive a coil spring 33 which is disposed between the upper end of the slot and the bolt in said slot. Thus the cup retaining clip 27 is vertically slidable on arm 19 against a downward pressure exerted by coil spring 33. Cup-supporting bracket 20 is substantially L-shaped and is secured to stand 10 below the marginal extremity of operating arm 19 by screws 34 to provide a supporting arm 35 for the base of cup 21. Arm 35 is curved adjacent its outer marginal end to provide a hump 36 adapted to project into the concave undersurface of the base of said cup.

When it is intended to mix a drink, cup 21 is placed against operating arm 19 with the rim of the cup under the hook portion 37 of clip 27 and the impeller assembly 14 inside the cup. Rearward pressure against operating arm 19 causes the motor and impeller assembly to rotate about its pivotal axis into a vertical operable position. This action against the operating arm 55 moves the switch operating element 26 to closed

circuit position against the resistance of its biasing means to start the motor and impeller assembly. At the same time as arm 19 is pushed rearwardly it is necessary to exert an upward pressure so that the rim of the cup lifts the hook 37 causing the cup retaining clip 27 to slide upwardly on arm 19 against compression of the coil spring 33. In this manner the shoulder of the base of cup 21 is free to pass over the hump 36 of cup supporting arm 35.

The motor and impeller assembly are held in their vertical position by pressure of the cup against the operating arm 19, the cup being retained by downward pressure of retaining clip 27 against the compression of coil spring 33 which forces the cup into supporting engagement with supporting arm 35. With the cup in its vertical position hump 36 is projected into the concave undersurface of the cup base so that the shoulder of the base of the cup is latched between the stand 10 and the hump 36. In order to remove the cup it is merely lifted to compress spring 33 and is drawn outwardly and downwardly. This releases the pressure on operating arm 19 and the biasing means of switch 23, acting through the switch operating element 26, exerts pressure against the motor and impeller assembly to assist in returning said assembly to its normal tilting position. At the same time, the switch is moved to its open circuit position.

It has been found that operators frequently neglect to turn off a drink mixing machine when the drink has been properly mixed. This is particularly so during the rush hours when operators are otherwise engaged in serving customers. With this in mind the present invention provides a standard type of normally closed thermal time switch which functions automatically to open the motor circuit after the drink mixing device has been in operation for a predetermined length of time and which closes automatically after being open for a predetermined period. This switch which is indicated at 38 is preferably mounted in the base of stand 10 as shown and is connected in series with switch 23.

Having thus described what I believe to be the preferred embodiment of this invention, it will be understood that various modifications may be resorted to within the scope and spirit of the invention as hereinafter claimed.

I claim:

1. A drink mixing device of the character described, comprising a vertically disposed supporting structure, a pair of laterally extending supporting brackets arranged to project from one side of said supporting structure adjacent the upper end thereof, a motor having trunnions arranged for eccentric support of the motor, said motor being adapted to swing about the horizontal axis provided by said trunnions between said supporting brackets to assume a normally tilted position, an impeller assembly extending downwardly from a motor shaft and swingable therewith whereby said impeller assembly will be normally biased away from the supporting structure, a motor switch mounted on said supporting structure, a switch actuating element, means for resiliently biasing said element to a switch opening position, said element being arranged in the path of movement of the motor and adapted to project the motor and impeller assembly away from the supporting structure,

an operating arm depending from said motor for moving the motor and impeller assembly against the resistance of the switch actuating element biasing means to the switch closing position, a cup retaining clip engageable with the rim of a mixing cup and carried by said operating arm, said clip being adapted to be vertically slidable on said arm, a spring biasing means mounted in said arm and adapted to exert resilient downward pressure on said cup retaining clip against upward pressure applied to the clip, and a cup supporting bracket immovably secured to the supporting structure for supporting the base of a mixing cup, said clip and said cup supporting bracket being arranged to cooperatively retain the mixing cup in clamping engagement and to secure the motor and impeller in the operating position when the motor switch is closed.

2. A drink mixing device of the character described, comprising a supporting base, an upright post mounted on said base and provided with a pair of spaced laterally extending brackets, a motor, an impeller assembly secured to the motor shaft to extend downwardly therefrom, said motor being eccentrically mounted between said brackets to normally provide biasing of the impeller assembly away from said post in an inoperative position and a switch mechanism resiliently biased to open position and arranged to be engaged and closed against the resistance of the switch biasing means by the motor when the motor and impeller assembly are swung in the switch closing position, said biased switch mechanism being adapted to project the impeller assembly to its normally biased position.

3. A mixing device according to claim 2, including a switch actuating element normally resiliently biased to a switch opening position, said element being arranged in the path of movement of the motor and impeller assembly and adapted to project said impeller assembly away from the upright post of the supporting structure to its inoperative position.

4. A mixing device according to claim 2, including an operating arm depending from said motor for moving the motor and impeller assembly against the resistance of the switch biasing means to the switch closing position, a cup retaining clip engageable with the rim of a mixing cup and carried by said operating arm, said clip being adapted to be vertically slidable on said arm against resilient downward pressure, and a cup supporting bracket secured to said upright post for supporting the base of a mixing cup, said clip and said cup supporting bracket being arranged to cooperatively retain the mixing cup in clamping engagement when the motor and impeller assembly are in the switch closing position.

MAX NATHANSON.
